UNITED STATES PATENT OFFICE.

VINCENT LOMBARDI, OF BROOKLYN, NEW YORK.

KNITTING MACHINE.

Application filed December 18, 1922. Serial No. 697,554.

To all whom it may concern:

I, VINCENT LOMBARDI, a citizen of the United States, residing at Brooklyn, in the county of Kings, State of New York, have invented certain new and useful Improvements in Knitting Machines, of which the following is a full, clear, concise, and exact description.

This invention relates to knitting machines and methods, and more particularly it relates to machines and methods, for knitting multi-color fabrics.

An object of this invention is to provide automatic means for knitting a multi-color fabric in which different portions of the fabric will be of different colors, the yarn which does not determine the color of the front of the cloth in any particular portion being carried along with the knitting but substantially concealed from the front of the fabric.

Another object is to provide adjustable means in a knitting machine for varying the pattern of the fabric at any time desired.

Another object is to provide means for producing a predetermined variation in the rise and fall of the needles of a knitting machine to cause desired variations in the fabric.

Another object is to provide for causing certain needles to rise at particular times while allowing neighboring needles to remain in their lowest positions.

Another object is to provide a machine for knitting a two-color fabric in which the yarn not in loops will be interlocked behind and between the loops of the other yarn.

Still another object is to provide an improved method of knitting whereby the results outlined above may be accomplished.

Other objects of the invention will in part be obvious and will in part appear herein-after.

One form of this invention will be herein-after described in detail in connection with a circular knitting machine for knitting multi-color fabrics. In this machine the above objects are attained by providing four different kinds of needles in case the machine is for two-color knitting. Two types have butts at the same relative position along their shanks, but the butts in one type

are short and in the other, long. The other two types are also characterized by having long and short butts with the butts differing in relative position compared to the first two types. This enables the needles having butts at one height to be operated by cams independent of other cams for operating the needles having butts at the other height. A further distinction can be made by cams of different sizes for operating only the needles with long butts or all the needles. The employment of four kinds of needles is of course only one way in which means may be provided for selectively operating the needles in a predetermined manner.

In locating the needles in a circular knitting machine those places where it is desired that the fabric be one of the colors, the needles having butts of one height are placed, the long and the short butts being alternated. At the other places where the fabric is to be of the other color the needles having butts at the other height are placed, the long and short butts being alternated. Suitable cam surfaces are provided for bringing all of the needles for one color up to form loops when that color yarn is passing while when the other yarn is passing alternate ones of these needles are partially raised still keeping their latches open and keeping the last formed loop around both the needle and the open latch. After the yarn of the second color is hooked by these partially raised needles they are lowered again. When the first yarn comes around again all of the needles for the first color are fully raised in turn to allow each old loop of the first color and the alternately hooked yarn of the second color to slip below the latch so that when each of these needles is lowered the old loops and the hooked yarn of the second color will slip over the tops of the needles and be replaced by the newly formed loops. This results in the yarn of the second color being interlocked behind the loops of other color, thereby providing a closely knitted fabric which does not have any loose dangling loops on the back side of the fabric which in previous fabrics were sources of constant trouble because of the liability of their being snagged and the yarn broken, thereby destroying the fabric. The yarn of the second

79

105

color in the machine of this invention is in the above manner locked between the loops of the first yarn without changing however to any substantial degree the appearance of 5 the front of the fabric.

The above described operation of the needles for one color is repeated by other cams for the needles of the second color.

Certain of the cams for the needles of each 10 color may if desired be made adjustable whereby for example after a certain number of rows are knitted the loop forming operations are reversed so that loops of the first color may be formed where formerly loops 15 of the second color were formed and vice versa. This invention in the form herein-after described in detail provides for the automatic adjustment of these cams whereby 20 reversals of the color of the fabric may be made at predetermined intervals. As will appear hereinafter these cams may be also automatically adjusted to knit the entire fabric of only one of the two colors desired thereby providing a further variation in the 25 fabric to provide both a checkered color and also a solid color.

This invention will be better understood by reference to the following detailed description taken in connection with the accompanying drawings in which Fig. 1 represents a view of a knitting mechanism constructed in accordance with this invention; Fig. 2 represents the fabric correctly spaced corresponding to the needles of Fig. 3; Fig. 3 is a sectional view of the knitting machine illustrating how certain cams of Fig. 1 may be automatically operated; Fig. 4 is a side view of the apparatus of Fig. 3; Fig. 4 is a detail view of the mechanism shown in Fig. 4; Fig. 5 is a top view of a portion of Fig. 4; Fig. 6 is a side view of a portion of Fig. 4; Figs. 7, 8, 9 and 10 illustrate cam means for the control chain of Fig. 4; Fig. 11 is a top view of the knitting machine; and Figs. 12, 13 and 14 represent enlarged views of one type of cloth made by this invention; Figs. 15 and 16 illustrate further the control mechanism of this invention; and Figs. 17, 18, 19 and 20 illustrate a modification of Fig. 15 in four different positions.

The manner in which cams are arranged to selectively raise the needles will be understood from Fig. 1 in which the stationary cylinder 60 is flattened out for convenience, although the ends are in the actual machine connected together to form a continuous cylinder. Along the outside of the cylinder 60 suitably supported and spaced in parallel relation are a plurality of needles numbered 1 to 54 inclusive. Needles 1 to 14, 21 to 34, and 41 to 54 have butts capable of being moved between surfaces 70 and 71 while the remaining needles have butts capable of being moved between other surfaces 72 and

73. The odd numbered needles have short butts as shown at 55 and 58, while the even numbered have long butts as at 56 and 57. For convenience in Fig. 1 the long butts are shown shaded while the short butts are unshaded in order to readily distinguish the kinds of needles. The needles operating between surfaces 70 and 71 are controlled in their upward and downward motion by cams 61, 62, 63 and 65 which are fixed to a cylinder rotating around cylinder 60 and also by cams 64 and 66 which are capable of adjustment either to be in the path of the butts or entirely out of the way. As shown in Fig. 1 cam 64 is in operative position 70 while cam 66 is in a non-operating position. Similarly needles having butts between surfaces 72 and 73 are controlled by cams 74, 75, 76, 77 and one of the adjustable cams 78 or 79, shown in the drawing to be cam 78. For most purposes, cam 78 should be in operating position when cam 64 is operating and similarly cam 79 should be in operation position when cam 66 is operating for reasons described hereinafter. 75

The type of machine shown in Fig. 1 is of the circular knitting machine type for knitting tubular fabric of two colors. Fig. 2 is a somewhat schematic top view of Fig. 1 and is placed in exact alignment with Fig. 1 to show the character of the fabric which lies just over the edge 60 of Fig. 1. The customary sinkers 80 separating the needle spaces are shown, while the showings such as at 81 illustrate the top view of needles having closed latches, the showings such as at 82 illustrating needles with open latches, which of course can be verified by noting the corresponding side views of the needles in Fig. 1. 100

As explained above member 60 is actually a stationary cylinder around which revolves another cylinder carrying the cams above described. The needles of course do not move laterally but are subjected only to an upward and downward movement due to the revolving cams. As is well understood in the art the needles undergo a cyclic operation in order to form the desired fabric. For convenience, the explanation of the operation of the machine will start with needles 1 and 2 which are in their lowermost position and, each having its latch closed and holding a loop of yarn 83 which for convenience will be called white yarn 110 since it is shown unshaded. The other yarn 84 which is shown shaded will be called black yarn. 115

Assuming that the cylinder carrying the cams is moving in a counter clockwise direction or from left to right across the sheet, cam 61 is the first cam to pass along the butts of needles 1 and 2. Cam 61 is of such a width that it will contact with and raise only those needles having the long butts. 120 125 130

Needle 1 will not be lifted by cam 61 but will remain with its butt along surface 71 similar to needles 3, 5, 7, 9, etc. The needle 2 however with a long butt will be raised by 5 cam 61 and will successively take positions similar to needles 4, 6, 8, etc. Needle 2 when raised by cam 61 will not be raised to its maximum top position but will be raised an amount sufficient to allow the latch to 10 open and have the loop surround both the shank and the latch but not raised far enough to allow the loop to slip over the end of the latch. The even numbered needles from 1 to 14 are then partially raised by 15 cam 61 while the odd numbered ones remain in their lowermost positions.

Cam 62 will next strike the needles 1 to 14 and the cam is of sufficient width to lower both the long butt needles and short butt 20 needles. However, since only the long butt needles of 1 to 14 have been raised it follows that only the long butt needles of 1 to 14 will be lowered by cam 62. The revolving cylinder carrying the cams also supports and carries along with it the yarn carriers shown in detail in subsequent figures. Located just above cam 62 is the yarn carrier for black yarn 84 so that the long butt needles of 1 to 14 will be lowered by cam 62 25 after black yarn 84 has been hooked by them. After the long butt needles of 1 to 14 are lowered by cam 62 they will be positioned the same as needles 26 to 29. The short butt needles 27 and 29 which were not raised by 30 cam 61 nor lowered by cam 62 have their latches closed and contain in their closed latches loops of the white yarn previously made. The long butt needles 26 and 28 which were pulled down by cam 62 have 35 their latches still open but with each hook containing both a loop of the white yarn and the straight portion of the black yarn within the hook and just above the white loop. The straight portion of the black 40 yarn will lie on top of the short butt needles such as 27 and 29.

The next cam to affect the needles having butts between surfaces 70 and 71 is cam 63 which is of such a width as to raise only the 45 long butt needles to the position shown for needles 32 and 34. This is again only a partially raised condition such as that produced by cam 61 above described. It will be noted that due to the raising of the long 50 butt needles by cam 63 the long butt needles each has (as shown at 34) its latch open with the loop of white yarn as well as the straight part of the black yarn on the side of the needle adjacent the observer while 55 the black yarn still remains above the closed latches of the short butt needles as shown at 33.

The next cam to operate the needles having butts between surfaces 70 and 71 is cam 64 which is of such a thickness as to raise 60

both the short and long butt needles and to raise them to their maximum height. Cam 64 thereby puts the needles in positions similar to 43, 44, and 45 since cam 64 in raising the long butt needles will allow the loop of 70 white yarn and the black yarn to slip below the end of the latch while for the short butt needles the black yarn, being on top of the hooks before the passage of the cam 64, will have the black yarn on the side of 75 the short butt needles away from the observer. That is cam 64 in raising both the short and long butt needles will cause the unlooped black yarn to follow a zig zag path in front of alternate needles and behind the 80 remaining needles for a purpose described later.

The next cam to operate the needles between surfaces 70 and 71 is cam 65 which will meet both the short butt and long butt 85 needles in their uppermost positions with all latches open and will lower both types. Supported immediately above the cam 65 is the carrier for the white yarn 83 which carrier of course rotates with the cams. 90 The yarn 83 will then be caught by these needles as they are lowered, each latch will be closed by the former loop bearing upwards against it and after each needle has reached near its lowermost position each 95 old loop will slip over the closed latch of the needle and over the edge of the fixed cylinder 60 so that when the needle has reached its lowermost position only the new 100 loop is around the needle. Due to the fact that the black yarn is on one side of the long butt needles and the opposite side of the short butt needles the black yarn for each long butt needle will slip over the end 105 of the needle and will lie beside the end of the old loop and across both parts of the new loop as will appear from the position of needle 54 in Fig. 2. The fabric shown in Fig. 2 is shown of course with the back side to the observer. For the loops formed by the 110 long butt needles the black yarn just slipped over each needle by cam 65 will lie entirely behind each loop formed thereby. For the short butt needles however the black yarn is already on the side of the needle opposite the observer so that when the old loop is slipped over a short butt needle by cam 65 and the white yarn is pulled through the old loop to form a new loop the black yarn 115 is caught and locked between the new and old loops as shown for example by the fabric opposite needle 53 of Fig. 2. The exact nature of the path taken by the black yarn through the white yarn loops will be better understood by reference to Figs. 12, 13 and 120 14 described later.

The long and short butt needles after being lowered by cam 65 have now completed a cycle begun by the cam 61 so that the needles after being lowered by cam 65 are 130

ready to be operated again by cams 61, 62, 63, 64 and 65 in the order named to form a new row of white yarn loops.

The above description has shown how the white yarn loops are formed. That portion of the fabric knitted by needles 1 to 14, 21 to 34, and 41 to 54 will be composed of white yarn loops. The remainder of the fabric knitted by needles 15 to 20 and 35 to 10 40 will be composed of black loops with the white yarn interlocked between the black loops in a manner now to be described.

Needles 15 to 20 and 35 to 40 have butts adapted to operate between surfaces 72 and 15 73, the even numbered needles having long butts and the odd numbered needles having short butts.

Cam 76 corresponds to cam 61 to raise the long butt needles. After this selective raising the needles encounter cam 77 which corresponds to cam 62 to cause the white yarn to be caught by alternate needles with open latches even after they are lowered by cam 77. After the passage of cam 77 needles 35 25 to 40 would look like needles 24 to 29 with the yarns reversed of course. Cam 77 is of sufficient width to lower both the long butt needles and the short butt needles, but for the arrangement shown with cam 79 not operating only the long butt needles are lowered. After cam 77 has passed the next cam is 74 of such a width as to selectively raise only the long butt needles. For the particular arrangement shown this selectivity is not utilized since with cam 78 in the position shown both the long butt and short butt needles will be fully raised thereby.

These needles next encounter cam 75 which corresponds to cam 65 for catching the black yarn and forming new loops, the white yarn being interlocked between the black loops in just the same manner as described for the white loops. After cam 75 is encountered the next cam is 76 and the above described cycle will be repeated as often as desired.

It thus will be seen that the needles 1 to 14, 21 to 34, and 41 to 54 will knit white loops with the black yarn on the back side of the fabric but interlocked in alternate loops, while needles 15 to 20 and 35 to 40 knit black loops with the white yarn on the back side of the fabric interlocked in alternate wales. The resulting fabric therefore has three broad white stripes separated by two narrow black stripes.

The above colors assumed for yarns 83 and 84 are of course merely illustrative as the two yarns may be of any desired colors or may be of the same color but differing in some other characteristic. In certain cases, in fact, yarns of the same color and characteristics may be used, it being possible to produce in this manner a fabric wherein a striped effect, for example, is obtained by

means of the breaks between adjacent groups of wales as between the wales *c* and *d* in Fig. 12.

The schematic showing in Fig. 1 is not strictly accurate as to the relative spacing of the stationary cylinder, the rotating cams and the needles since from Fig. 1 it appears that the revolving cams are between the needles and the stationary cylinder whereas in the actual machine the needles are between the cams and the stationary cylinder. This will all be better understood by reference to later figures.

As shown in Fig. 1 adjustable cams 64 and 78 are operative while cams 66 and 79 are inoperative. If however these four cams are adjusted so that cams 78 and 64 are lowered out of operating range and cams 66 and 79 are raised until operative the result will be that cam 66 will raise to their uppermost positions both the short butt and long butt needles whereby the needles will be raised sufficient to allow the old loops to slip over the end of each latch so that each needle will catch the black yarn 84 and 90 make new loops thereof. Cam 78 being lowered out of operative range will not raise the butts between surfaces 72 and 73 sufficient to cause these needles to make new loops of the black yarn. Only the long butt 95 needles will be partially raised by cam 74 and cam 75 coming along will cause the black yarn to be merely intertwined between them instead of being looped. Cam 79 being raised will cause both the long and short 100 butt needles to be raised to their uppermost position whereby when they encounter cam 77 the needles 15 to 20 and 35 to 40 will form new loops of the white yarn. Cam 64 being lowered out of operative position will 105 allow the partially raised long butt needles to encounter cam 65 whereby in a manner heretofore explained the white yarn will be merely intertwined between the needles operating between surfaces 70 and 71. 110

This reversal of cams 64, 66, 79 and 78 therefore results in the black yarn being knitted where the white yarn formerly was and the white yarn knitted where the black was. After several rows have been knitted in this manner cams 64, 66, 78 and 79 may be replaced in the positions shown in Fig. 1 whereby the color scheme will be reversed again. This changing of the four adjustable cams therefore enables a fabric to be knitted 115 resembling a checker board in color variations.

In view of the above explanations it will be apparent that if it is desired to make several white rows entirely around the fabric, cams 64 and 79 should be raised into operative positions while cams 66 and 78 should be inoperative. On the other hand if an entirely black row or rows of loops is desired around the whole cloth both cams 120 125 130

63 and 78 should be operative and cams 64 and 79 inoperative. Hereinafter will be described means whereby the character of the fabric may be changed automatically to take care of any predetermined pattern. Another possible variation is of course to have all four cams 64, 66, 78 and 79 raised whereby the well known jersey cloth would be knitted. Instead of having all the needles 10 knit jersey cloth, still another possible variation is to have cams 64, 78, and 79 in their uppermost positions and cam 66 in its lowermost position. This will cause needles 1 to 14, 21 to 34 and 41 to 54 to form the interlock cloth with loops of yarn 83 in front and yarn 84 interlocked in the rear of the loops of yarn 83, while the needles 15 to 20 and 35 to 40 knit loops of both yarns 83 and 84 in the front of the fabric thereby forming the jersey cloth. The resulting fabric therefore consists of stripes of interlock cloth separated by stripes of jersey cloth.

Fig. 3 discloses a sectional view of the machine of this invention disclosing more fully than schematic Fig. 1 the actual space relation of the various parts. The stationary cylinder 60 is mounted on a base plate 90 suitably supported. The revolving cylinder 91 acts as a support for the cams shown in Fig. 1. This revolving cylinder comprises a base 92 moving in a groove formed in the stationary plate 90. An upright member 93 mounted on the revolving plate 92 serves as the direct support for the fixed cams of Fig. 1. The sectional view shown in Fig. 3 shows one of the adjustable cams 64 holding a needle 44 in its uppermost position. This adjustable cam 64 is supported by a machine screw 94 which is fastened to an upright rod 95 capable of being moved up and down in a hole or slot located in the revolving cylinder. A similar slideable rod located in a plane below rod 95 is provided for moving the adjustable cam 79 of Fig. 1. The manner in which these rods are moved automatically to render cams 64 and 79 operative or non-operative will be described later.

Located between the stationary cylinder 60 and the revolving cylinder 91 are the various types of needles shown in Fig. 1. These needles are arranged in a circle around the fixed cylinder 60 and are held in grooves in the face of this cylinder by a coiled spring 96 serving to hold the needles in position. This arrangement of supporting the needles and the character of the fixed cylinder is in accordance with standard practice and is described here merely as an aid to the understanding of this invention. Projection 97 is one side of the slot in which rests the needle 44. Below projection 97 the slot is not so deep but ends at the surface 98 which is in sliding contact with the adjacent face 99 of the revolving cylinder 91. Resting in grooves on top of the fixed cylinder 60 and extending over the horizontal plate 99 which rotates with the revolving cylinder 91 are the customary sinkers 80 which in a manner well known in the art serve to push the cloth away from the knitting positions in a predetermined manner. There is of course a sinker between each pair of needles. Each of these sinkers on the upper side is slotted so as to form a groove in which rests a projection 101 of a plate 100 which revolves with the cylinder 91. This plate 100 extends entirely around the machine and due to an irregularity in the location of the projection 101 serves to pull the sinkers in at predetermined times and keeps them out at other times,—as is done in standard practice.

Both of members 99 and 100 are supported by a vertical rod 102 which is mounted on the revolving base plate 92. This rod 102 also serves to support at its upper end a spool of yarn (not shown) from which the yarn 83 comes. The yarn guide 103 is suitably fastened to the plate 100.

The needle 44 shown in Fig. 3 is of the long butt type and is in its uppermost position due to the fact that it is riding on the upper surface of the adjustable cam 64. The lowermost position for this needle is when the long butt is resting against the surface 71 of the movable cylinder. The butts of all the needles 1 to 14, 21 to 34 and 41 to 54 of Fig. 1 move between the two surfaces 70 and 71, being raised or lowered by the cams 61, 62, 63, 64, 65 which are attached to the revolving cylinder 91 between these surfaces.

Needles 15 to 20 and 35 to 40 of Fig. 1 have their cams operating between surfaces 72 and 73 of the cylinder 91. On a different section than the section shown for cam 64 is shown the cam 76 on which is riding a long butt needle while a short butt needle is resting on the surface 73 the cam 76 being of insufficient width to raise the short butt needle.

Rod 95 which supports the adjustable cam 64 has a ball and socket joint with the end 104 of a member 105 pivoted at 106. Mounted on the short arm of the pivoted member is a contact member one end 107 of which is adapted under certain conditions to contact with a stationary disc 108 while its other end 109 is adapted under certain conditions to contact with a stationary disc 110. The discs 108 and 110 are so mounted on a common support 111 that either disc 108 is adapted to contact with end 107 or disc 110 is adapted to contact with end 109 depending on whether support 111 is in a raised or a lowered position. Therefore when support 111 is in a raised position disc 108 will hit end 107 and cause the pivoted member 105 to raise rod 95 so that cam 64 is in an operative position, as

shown. A suitable stop member 112 limits the upward movement of the pivoted arm 105. In order to maintain the arm 105 in its uppermost position after disc 108 has been passed a spring member 113 is made to ride over a curved surface 114 which is suitably supported by revolving cylinder 91 from a point not shown in the sectional view of Fig. 3. The curved end 10 of member 114 is faced away from the observer. Due to the tendency of spring 113 to spring outward the spring 113 is held on the side of member 114 adjacent stop 112 when member 105 has been raised by disc 108. 15 On the other hand if support 111 is in a lowered position cylinder 91 in revolving will cause disc 108 to contact with end 109 and cause the pivoted arm 106 to be lowered until stopped by the stopping member 115. 20 During the lowering of arm 105 the spring 113 will ride over the curved end of member 114 and lie on the side of the curved surface adjacent stop 115. This lowering of member 105 lowers cam 64 out of its operating range.

An end view of cam 79 is shown in Fig. 3. This adjustable cam is held by a machine screw to a rod not shown but similar to rod 95, located in a plane beyond rod 95 and working in a parallel hole to that of rod 95. This rod has a ball and socket joint 116 with a pivoted member 117 which is capable of being raised or lowered by discs 118 and 119 mounted on a movable support 120 in the same manner as member 105. Stop members 121 and 122 are provided for the pivoted member 117 and this pivoted member may be biased in either its upper position or lower position by a spring member such as member 113. As shown in the drawing disc 118 has lowered pivoted member 117 to its lower position whereby cam 79 is placed in its inoperative position.

Similar arms pivoted as arms 105 and 117 may be provided on the revolving cylinder at points opposite the other two adjustable cams 66 and 78, with this difference however that the pivoted arm moved by either disc 108 or 110 should control the lower cam 78 while the pivoted arm moved by discs 118 and 119 should control the upper cam 66. This is for the reason as shown in Fig. 1 that cams 64 and 78 should be raised when cams 66 and 79 are lowered and cams 64 and 78 should be lowered when cams 66 and 79 are raised in order to get the checker board effect.

The manner in which the cylinder 91 may be revolved is not material to this invention but may be accomplished in any of the ways known in the art. For example the lower side of base plate 92 may be provided with teeth which cooperate with a cog wheel to rotate the cylinder. The cog wheel (not shown) may be connected to a source of

power such as an electric motor in any suitable manner.

The manner in which the supports 111 and 120 may be raised or lowered may be understood from Fig. 4 which is a side view of the machine taken near the cross section of Fig. 2. The lower end of support 111 is pivoted to a horizontal arm 123 pivoted at 124 and at the end opposite the pivot is adapted to be held up by a latch 125 which is pressed against the arm 123 by a spring 126. Whenever the latch 125 is released the arm 123 falls down until the stop 127 rests on plate 90. Suitably mounted below the arm 123 and the similar arm 128 for the support 120 is a cog wheel 136 which works with a link chain 129 which fits over the teeth of wheel 136 so that the rotation of wheel 136 pulls the chain around. The chain has mounted on predetermined links a plurality of cams such as shown in Figs. 7, 8 and 10. Cam 130 is of the type shown in Fig. 7 which has a projection such as to contact with the lower surface of pivoted arm 123 to raise it until latch 125 holds it in place. When cam 131 (see Fig. 8) has reached the position shown for cam 130 the projecting surface is such that it will contact with the lower surface of arm 128 and raise it. Arm 128 on being raised will push latch 125 out far enough to allow arm 123 to fall down before arm 128 has reached its uppermost position where it is held by the latch which has returned after arm 123 has dropped.

The framework 133 to which the arms are pivoted is attached of course to the revolving cylinder 91 and with the upright supports in the position shown in the drawing disc 108 will contact with end piece 107 and cause cam 64 to take the raised position shown in Fig. 1. Disc 118 on the upright member 120 will contact with the end piece 134 and cause cam 79 to be lowered as shown in Fig. 1.

A similar framework may be mounted on the revolving cylinder opposite cams 66 and 78 except that the pivoted member controlling cam 66 should be the lower of the pair so as to be operated by either discs 118 or 119, while the pivoted member for the other disc should be pivoted above the other pivoted member of the pair whereby cam 78 will be controlled by discs 108 and 110.

With the above arrangement it will be apparent that as long as arm 123 is held by latch 125 and arm 128 is in its lowermost position cams 64 and 79 will be inoperative and cams 66 and 78 will be operative so that the needles having butts on the higher level will knit loops from the white yarn while those on the lower level will knit loops of the black yarn. This will continue even after the link carrying the cam 130 has passed since arm 123 will be contin-

ued to be held by the latch in its upper position and arm 128 will remain in its lower position.

However as soon as wheel 136 has revolved to a sufficient extent that cam 131 is operative to raise arm 128 and lower arm 123 as above described cams 64 and 78 will be inoperative and cams 66 and 79 will be operative. This results in the needles having butts on the lower level knitting loops of the white yarn and those on the upper level knitting loops of the black yarn,—whereby a checkered effect is produced. Cams such as 130 and 131 may be suitably spaced along the chain 129 to give the reversals when desired. Wheel 136 should preferably be geared to the mechanism driving the revolving cylinder 93 so that chain 129 moves along one link for a definite number of complete revolutions of the cylinder 93.

At certain places along the chain it may be desired to have an attachment such as that shown in Fig. 9 which has no projection sufficient to raise either arm 123 or 128,—but merely has a horizontal projection 137 extending away from the chain on the side opposite the observer. This projection when it has reached the position shown for cam 130 in Fig. 4 will contact with a special control arm 138 and tend to raise the same. This control arm is supported by the pivoted latch 125 at one end and by a pivoted member 139 at the other end. The pin 137 coming into contact with the projection 140 will push the latch back against the spring a sufficient distance to allow that arm of the two arms 123 and 128 which is held up by latch 125 to fall down so that both arms 123 and 128 are in their lower positions and remain so until a cam such as 130 or 131 comes along to raise one or the other.

From the above description it will be apparent that with both arms 123 and 128 raised all cams 64, 66, 78 and 79 will be operated so that both types of needles knit not only black loops but white loops as well, thereby giving a variation to the checkered fabric whenever desired. This would take place if cams similar to cam 175 of Fig. 10 were present on chain 129 of Fig. 4.

It is of course understood that if it is desired the cloth may not be made checkered but the one type of needle may continue to knit one color loops while the other type knits loops of the other color.

Fig. 4 illustrates the manner in which the latch 125 is pushed back to release one of the arms 123 or 128.

Fig. 5 shows a top view of the arms of Fig. 4 in order to make more apparent the space relation of numbers 123 and 128.

Fig. 6 is an end view of the supporting and operating means for the discs 108, 110, 118 and 119 of Fig. 4 and no further expla-

nation of the various parts is believed necessary.

Fig. 11 is a top view partly in cross section of a machine of this invention taken along several planes as will be understood by comparing Figs. 3 and 11. The various parts have been straightened out for the sake of simplicity although as described above the machine is a circular machine with the needles arranged in the form of a circle instead of in a straight line as in Fig. 11. The section 140 is taken at a point of Fig. 3 alongside cam 64 and shows the depth of the slots in which the needles work. Section 141 is taken at a higher level above cam 64 and shows the coiled spring 96 which holds the needles in place. Section 142 is taken at a still higher point where shelf 97 is placed to provide a rest for the revolving plate 99 of Fig. 3. The view just to the right of section 142 shows the tops of the sinkers 80. Lines 143 and 144 indicate the boundaries of the cam surface which travels over the sinkers 80 and pulls the sinkers in as shown at position 145, which correspond to the knitting position. The arrangement of the cam 101 of Fig. 3 should be such as to pull the sinkers in in this manner at every knitting position as is well known in the art. The remaining parts of Fig. 11 are obvious from the previous descriptions. The end pieces 146 and 147 are attached to pivoted arms 148 and 149 for controlling respectively cams 78 and 66 in the same manner as pivoted arms 105 and 117 control the other two adjustable cams 64 and 79.

These end pieces 105, 134, 146 and 147 may be of spring material if desired or they may be of sufficient thickness and material to be rigid so as not to absorb any part of the motion which would otherwise be impressed on the arms operating the cams.

Figs. 12, 13 and 14 illustrate a fabric of a type which may be produced by the present invention; Fig. 12 being a diagrammatic plan view of the fabric; Fig. 13 is a diagrammatic sectional view, and Fig. 14 an enlarged fragmentary view of the fabric. These figures illustrate a fabric composed of two yarns 150 and 151, the former of which is unshaded and will be referred to as white yarn, and the latter of which is shaded and will be referred to as black yarn. The fabric, as exemplified in Fig. 12, comprises a left-hand portion, in which the black yarn is looped, and a right-hand portion, in which the white yarn is looped, three of the wales of the black yarn being shown at *a*, *b* and *c*, and four of the wales of the white yarn being shown at *d*, *e*, *f* and *g*. In this particular fabric, the unlooped portion of the white yarn is interlocked with the black yarn in the wales *a* and *c*, and is carried entirely to the rear of the black

yarn in the wale *b*; while the unlooped portion of the black yarn is interlocked with the loops of the white yarn in the wales *d* and *f*, and is carried entirely to the rear of the white yarn in the wales *e* and *g*.

An arrangement of this type, wherein the unlooped portions of the yarns are interlocked in alternate wales of the looped portions of the other yarns, gives a maximum of interlocking, while preventing the formation of dangling loops so frequently present on the inside of a two-color knitted fabric; the fabric knitted by the present invention having no dangling loops, even at the point between the wales *c* and *d*, where the color of the front of the fabric changes. It will be noted that the fabric shown in Fig. 12 is somewhat different from the fabric shown in Fig. 2, in that there is an interlock at each of the adjacent wales of different colors *c* and *d*; whereas in the fabric shown in Fig. 2, there would be an interlock only at one of these wales, the next interlock occurring in a wale which would correspond to the wale *e*. It will thus be obvious that fabrics having a variety of interlocking arrangements may be produced by the present invention, all of which are nevertheless substantially similar and capable of being readily produced by a machine of the type illustrated. For example, a fabric of the character illustrated in Fig. 12 might be produced by a series of needles arranged as in Fig. 1, except that the needles 20 and 40 would be omitted. Still another arrangement might be produced by the omission of the needles 21 and 41.

It will be observed from Fig. 14 that the black yarn is very tightly drawn so that very little thereof is visible from the front of that portion of the fabric wherein the white yarn is looped. Thus there is produced a fabric wherein the unlooped portion of the yarn, while being securely interlocked, does not substantially affect the character of the front of the fabric. It will, of course, be obvious that there may be produced by the present invention fabrics of various types, and fabrics in which the yarns constituting the same may be more or less tightly drawn according to the type of fabric which it is desired to produce.

It will be apparent from the above description that the two color fabric is knitted without the requirement of the so-called "yarn changers" known in the art which function at predetermined times to replace one color yarn whereby the color is changed. These yarn changers are objectionable for many reasons one being that they cause the formation of long loose dangling loops on the back side of the fabric.

Figs. 15 and 16 illustrate more in detail the manner in which the four adjustable cams 64, 66, 78 and 79 of Fig. 1 may be con-

trolled by the discs 108, 110, 118 and 119. As shown in Fig. 15 the levers 123 and 128 are set to cause disc 108 to contact with the lower ends of arms 148 and 105 whereby cams 64 and 78 are raised to the operating positions shown for them in Fig. 1. Disc 118 however will hit the upper ends of arms 149 and 117 causing cams 66 and 79 to be lowered out of operating position as shown in Fig. 1. The positions actually shown in Fig. 16 are the positions reached after contact has been made with discs 108 and 118 as just described.

Fig. 16 shows lever 123 down and lever 128 up whereby disc 110 is in position to contact with the upper ends of arms 148 and 105 whereby cams 64 and 78 are lowered out of operating position. Disc 119 is in position to contact with the lower ends of arms 149 and 117 to raise cams 66 and 79 into operating position. As previously described the alternate setting of the cams as shown in Figs. 15 and 16 will give the fabric a checkerboard appearance.

Figs. 17, 18, 19 and 20 illustrate four of the possible positions of the cams of a modification of the structure illustrated in Fig. 3 for controlling cams 64, 66, 78 and 79 of Fig. 1.

By means of the control mechanism shown in these four figures cams 64 and 78 may be made operative for causing the upper level needles to form loops of yarn 83 and the lower level needles to form loops of yarn 84; or cams 79 and 66 operative to cause the upper level to loop yarn 84 and the lower level to loop yarn 83; or cams 64 and 79 operative to cause the needles on both levels to knit loops of only yarn 83; or cams 66 and 78 operative whereby all the needles loop only yarn 84.

Referring now to Fig. 17 the cams 64, 66, 78 and 79 are as in the previous figures supported by pivoted arms 156, 157, 158, and 159. The means for setting these cams however is somewhat different as will now be described. The standard 160 is similar to standard 111 of Fig. 3 except that three control discs 161, 162, and 163 are mounted thereon. Standard 164 is also provided with three suitably spaced control discs 165, 166, and 167. On Fig. 17 the control lever 170 for support 160 is shown in its raised position and control lever 171 for support 164 is shown in its lowered position, the positions for levers 170 and 171 being due to the passage along the control chain of a cam such as that shown in Fig. 7. With standards 160 and 164 in the positions shown in Fig. 17 disc 162 is arranged to contact with the upper end of arm 158 and the lower end of arm 156 to make cam 64 operative and cam 66 inoperative. With standard 164 in the position shown disc 165 is arranged to contact with the upper end of arm 157 and

render cam 79 inoperative while disc 167 is arranged to contact with the lower end of arm 159 and render cam 78 operative. Fig. 17 therefore shows how the cams of Fig. 1 may be set to cause the upper level needles to knit yarn 83 and the lower level needles to knit yarn 84.

Fig. 18 shows control levers 170 and 171 after the passage of a cam such as shown in Fig. 8 to raise lever 171 and lower lever 170. This lowers standard 160 and raises standard 164. This relation is such as to permit: (a) disc 163 to contact with the lower end of arm 158 to make cam 66 operative; (b) disc 161 to contact with the upper end of arm 156 to render cam 66 inoperative; (c) disc 166 to contact with the upper end of arm 159 to render cam 78 inoperative; and (d) disc 168 to contact with the lower end of arm 157 to render cam 79 operative. The positions taken by the four adjustable cams after passing by the standards 160 and 164 in the positions shown in Fig. 18 will therefore result in the upper level needles knitting yarn 84 and the lower level needles knitting yarn 83.

Fig. 19 illustrates both of the standards 160 and 164 raised and caught by the latch as would be the case after the passage along the control chain of a cam such as that in Fig. 10. With both standards raised (a) disc 162 contacts with the upper end of arm 158 and the lower end of arm 156 whereby cam 66 is made inoperative and cam 64 is made operative; (b) disc 166 contacts with the upper end of arm 159 and the lower end of arm 157 to make cam 79 operative and cam 78 inoperative. This by referring to Fig. 1 makes both the upper and lower level needles knit yarn 83 with yarn 84 being interlocked on the back side.

Fig. 20 illustrates both of the standards 160 and 164 lowered as would be the case after the passage along the control chain of a cam, such as that shown in Fig. 9. With both standards lowered (a) disc 110 contacts with the upper end of arm 105 to render cam 64 inoperative; (b) disc 163 contacts with the lower end of arm 158 to make cam 66 operative; (c) disc 165 contacts with the upper end of arm 157 to render cam 79 inoperative; and (d) disc 167 contacts with the lower end of arm 159 to render cam 78 operative. As evident from Fig. 1 this will cause both the upper level and lower level needles to knit loops of only yarn 84 with yarn 83 interlocked in alternate wales on the back side of the fabric.

It is obvious that with the cam control mechanism various color designs may be knitted without the requirement of the so-called "yarn changers" and without the formation of any dangling loops. It is of course understood that while only two yarn carriers are disclosed in Fig. 1 that as many

yarn carriers as desired may be employed thereby enabling still further variations to be made in the design of the fabric. One such an arrangement for example would be to employ four yarn carriers three of white yarn for instance and the fourth of black yarn. The adjustable cams opposite each yarn carrier may then be set to have the upper level needles knit loops from all three white yarns and have the lower level needles knit loops only from the black yarn. This will give a pleasing effect, since each black loop will be bigger than the white loops and the three white yarns interlocked together behind the loops of the black yarn. Other modifications of course will be evident to those skilled in the art, since the machine above described may have many and widely different embodiments without departing in any wise from the spirit of this invention as defined in the appended claims.

It is to be understood that the following claims are intended to cover all of the generic and specific features of the invention herein described, and all statements of the scope of the invention which, as a matter of language, might be said to fall therebetween.

The invention claimed is:

1. A knitting machine comprising a stationary vertical cylinder having needles arranged in grooves therein, each of said needles having a hook and a pivoted latch member at its upper end and a projecting butt along the shank of the needle, a plurality of yarn carriers for independent yarns, a second cylinder rotating outside of said first cylinder, cam means arranged on said second cylinder and contacting with said butts for causing certain groups of said needles to knit loops of one yarn, similar cam means for causing other groups of said needles to knit loops of a second yarn, means for causing said second yarn to be interlocked between the loops of alternate wales of the first yarn while being carried to the rear of the remaining wales of said first yarn, and means for causing said first yarn to be interlocked between the loops of alternate wales of the second yarn while being carried to the rear of the remaining wales of said second yarn.

2. A knitting machine according to claim 1 having means responsive to the operation of said machine for reversing the yarns knitted by the various groups of needles.

3. A machine for knitting a plurality of independent yarns into a fabric comprising a circular row of needles, a yarn carrier, a second yarn carrier, means for causing a relatively large number of adjacent needles to knit loops of said first yarn, means for causing a relatively large number of other needles in a second group to knit loops from said second yarn, means for causing alter-

nate needles of said first group to be moved a distance sufficient to catch the yarn from said second carrier, the said distance being insufficient to allow the previously formed loops on said alternate needles to slip over the ends of the open latches of the needles, means acting subsequent to the passing of the second yarn carrier to pull back said alternate needles to their former positions, 5

10 said first means acting when said first yarn carrier is passing to move all the needles in said first group a distance sufficient to catch said first yarn to form loops thereof and sufficient to cause the second yarn previously 15 caught by alternate needles to slip over the open end of the needle latches on to the shanks of the needles whereby said second yarn is interlocked between the loops of said first yarn in alternate wales of the portion 20 of the fabric knitted by said first group of needles and similar means for causing said first yarn to be interlocked between the loops of said second yarn in alternate wales of the portion of the fabric knitted by said 25 second group of needles.

4. A knitting machine for knitting a plurality of independent yarns into a fabric comprising a circular row of needles, a yarn carrier for one yarn, a second yarn carrier for a second yarn, means for causing certain groups of said needles to knit loops of said first yarn, means for causing intermediate groups of said needles to knit loops of said second yarn, each of said groups comprising a relatively large number of needles, means operating on the needles of said certain groups whereby when the needles of said certain groups are raised ready to knit loops of said first yarn the second yarn is intertwined between the shanks of the needles of said certain groups being in front of alternate needles and behind the remaining needles, said first means subsequently causing the needles of said certain groups to be lowered to form another row of loops of said first yarn whereby said second yarn is interlocked between the loops of alternate wales of said first yarn, and means for similarly interlocking said first yarn between the loops of alternate wales of said second yarn. 30

35 40 45 50

5. A knitting machine for knitting a plurality of independent yarns into a fabric comprising a circular row of needles, a yarn carrier for one yarn, a second yarn carrier for a second yarn, means for causing certain groups of said needles to knit loops of said first yarn, means for causing intermediate groups of needles to knit loops of said second yarn, each of said certain and said intermediate groups comprising a relatively large number of needles, means for causing alternate needles in each of said certain groups to be raised a distance sufficient to catch the 55 60 65 70 75 80 85 90 95 100 105 110 115 120 125 130

second yarn when the second yarn carrier is passing, the said distance being insufficient to enable the previously formed loops of the first yarn to clear the needle latches, means acting after the passage of the second yarn carrier and before the next passage of first yarn carrier for lowering said alternate needles, whereby the second yarn is caught along with the previously formed loop of the first yarn within the hook of each of the 70 75 80 85 90 95 100 105 110 115 120 125 130

second needles while the second yarn lies on the back side of the first yarn loops previously formed by the remaining needles of said certain groups, said first means subsequently forming another row of loops of said first yarn whereby the second yarn is interlocked between the loops of alternate wales of the fabric knitted by said certain groups of needles and means for similarly interlocking said first yarn between the loops of alternate wales of the portion of the fabric knitted by said intermediate groups of needles.

6. A knitting machine for knitting a plurality of independent yarns into a fabric comprising a circular row of needles, a yarn carrier for one yarn, a second yarn carrier for a second yarn, means for causing certain groups of said needles to knit loops of said first yarn, means for causing intermediate groups of said needles to knit loops of said second yarn, each of said groups comprising a relatively large number of needles, means operating on the needles of said certain groups whereby when the needles of said certain groups are raised ready to knit loops of said first yarn the second yarn is intertwined between the shanks of the needles of said certain groups being in front of alternate needles and behind the remaining needles, said first means subsequently causing the needles of said certain groups to be lowered to form another row of loops of said first yarn whereby said second yarn is interlocked between the loops of alternate wales of said first yarn, and means for similarly interlocking said first yarn between the loops of alternate wales of said second yarn. 100 105 110 115 120 125 130

7. A knitting machine of the cylinder type for knitting a plurality of independent yarns into a fabric comprising a circular row of needles, a yarn carrier for one yarn, a second yarn carrier for a second yarn, rotating cam means for causing all the needles in certain groups of said needles to be raised prior to the passage of first yarn carrier and subsequently lowered whereby loops of said first yarn are formed, a second rotating cam means for causing intermediate groups of said needles to be raised prior to the passage of said second yarn carrier and subsequently lowered whereby loops of said second yarn are formed, each of said certain and said intermediate groups comprising a relatively large number of needles, cam means for 115 120 125 130

9. In a machine for combining a plurality of yarns into a fabric, in combination, a plurality of yarn feeds for independent yarns, a row of needles, and mechanism for operating said needles including means for causing a group of adjacent needles to be placed in a fully advanced position to receive yarn at one of said feeds, means for causing another group of adjacent needles to be placed in a fully advanced position to receive yarn at a second of said feeds, means for causing certain of the needles of the first group to be placed in a partially advanced position to receive yarn at said second feed while the remainder of the needles of the first group are in a retracted position, and means for causing certain of the needles of said other group to be placed in a partially advanced position to receive yarn at said second feed while the remainder of the needles of said other group are in a retracted position.
10. In a machine for combining a plurality of yarns into a fabric, in combination, a series of groups of needles and mechanism for operating said needles, said mechanism including means fully to advance all the needles of certain of said groups and to retract the same, means operative intermediate successive operations of the aforesaid means partially to advance certain of the needles previously actuated and to retract the same, means fully to advance all the needles of certain other of said groups and to retract the same, and means operative intermediate successive operations of the last-mentioned means partially to advance certain of the previously actuated needles and to retract the same, whereby there is produced a fabric wherein each yarn presents a looped portion and an unlooped portion, the unlooped portion of each yarn extending along the back of a section of the fabric wherein looped portions of certain other of the yarns are interknit and being interlocked between loops of adjacent rows in certain of the wales thereof.
11. In a machine for combining a plurality of yarns into a fabric, in combination, a plurality of yarn feeds for independent yarns, a row of latched needles each comprising a yarn receiving member and a shank, and being movable longitudinally of the shank to advanced positions wherein said yarns may enter said yarn receiving members, and mechanism for operating said needles, said mechanism including means to cause a plurality of adjacent needles to be placed in an advanced position to receive yarn at one of said feeds, means for causing other adjacent needles to be placed in an advanced position to receive yarn at a second of said feeds, means for causing alternate needles of the first group to be placed in a partially advanced position to receive
5. enable the previously formed loop on each of said alternate needles to clear the needle latch, cam means for subsequently lowering said alternate needles after the second yarn is caught; said first rotating cam means operating while said second yarn is caught by said alternate needles for raising and lowering all of the needles of said certain groups to form loops of said first yarn whereby as the last mentioned loops are formed the second yarn is interlocked between loops of alternate wales of said first yarn and means for similarly interlocking said first yarn between the loops of alternate wales of said second yarn.
20. 8. A knitting machine of the cylindrical type for knitting a plurality of independent yarns into a fabric comprising a circular row of needles arranged to form a cylinder, a yarn carrier for one yarn, a second yarn carrier for a second yarn, certain groups of said needles being arranged to knit loops of said first yarn, intermediate groups being arranged to knit loops of said second yarn, each of said groups comprising a relatively large number of needles, alternate needles in each of said certain groups having long butts a definite distance from the needle latch, the remaining needles of said certain groups having short butts the same distance from the needle latch, alternate needles in each of said intermediate groups having long butts a different distance away from the needle latches, the remaining needles of said intermediate groups having short butts the same distance away from the needle latches as said last mentioned long butts, cam means operating on the butts of all of the needles in said certain groups for knitting loops of said first yarn, cam means operating on the butts of all of said needles of said intermediate groups for knitting loops of said second yarn, cam means operating only on the long butts of the needles in said certain groups for partially raising and lowering alternate needles to catch the second yarn without knitting loops of the second yarn but causing the second yarn to be interlocked between the loops of alternate wales of said first yarn, while being carried to the rear of the remaining wales of said first yarn, and means operating only on the long butts of the needles of said intermediate groups for partially raising and lowering alternate needles to catch the first yarn without knitting loops thereof while causing the first yarn to be interlocked between the loops of alternate wales of said second yarn, while being carried to the rear of the remaining wales of said second yarn.

- yarn at said second feed while the remainder of the needles of the first group are in an unadvanced position, and means for causing alternate needles in said other group to be placed in a partially advanced position to receive yarn at said first feed while the remainder of the needles of said other group are in an unadvanced position.
12. In a machine for combining a plurality of yarns into a fabric, in combination, a plurality of yarn feeds for independent yarns, a row of needles each comprising a yarn receiving member and a shank, and being movable in a direction longitudinal of the shank to advanced positions wherein said yarns may enter said yarn receiving members, and mechanism for operating said needles, said mechanism including means to cause one group of adjacent needles to be placed in an advanced position to receive yarn at one of said feeds, means for causing another group of adjacent needles to be placed in an advanced position to receive yarn at a second of said feeds, means for causing only certain of the needles of the first group to be placed in an advanced position to receive yarn at said second feed, and means for causing only certain of the needles of said other group to be placed in an advanced position to receive yarn at said first feed.
13. In a machine for combining a plurality of yarns into a fabric, in combination, a plurality of yarn feeds for independent yarns, a row of knitting needles, and mechanism for advancing and retracting said needles, said mechanism including means to actuate a plurality of adjacent needles to cause them to interknit loops of certain of said yarns, and to interlock unlooped portions of certain other of said yarns between loops of said certain of said yarns in adjacent rows in alternate wales thereof while being carried to the rear of the loops in the remaining wales, and means to actuate another needle of said row to cause the same to interknit loops of said certain other of said yarns.
14. A knitting machine comprising a vertical circumferentially complete row of latched needles, a yarn carrier for one yarn, a second yarn carrier for the second independent yarn, means to raise and lower certain groups of said needles to knit loops of the first of said yarns, means to raise and lower other groups of said needles to knit loops of said second yarn, means partially to raise and lower alternate needles of said certain groups to cause the unlooped portion of said second yarn to be placed in position to be interlocked in substantially alternate wales of the loops of said first yarn between the two sides of a loop in one row and the two sides of a loop in an adjacent row while causing the unlooped portion of said second yarn to be carried entirely behind intermediate wales of said first yarn, and means partially to raise and lower alternate needles of said other groups to cause the unlooped portion of said first yarn to be placed in position to be interlocked in substantially alternate wales of the loops of said second yarn between the two sides of a loop in one row and the two sides of a loop in an adjacent row while being entirely to the rear of the intermediate wales of said second yarn.
15. In a machine for incorporating a plurality of yarns into a fabric, in combination, a row of needles, a plurality of separate yarn carriers for independent yarns, means for causing a group of adjacent needles to be fully advanced to receive the yarn from one of said yarn carriers, means for causing another group of adjacent needles to be fully advanced to receive yarn from a second of said yarn carriers, means for causing alternate needles of said first group to be partially advanced to receive yarn from said second yarn carrier while the remaining needles of said first group are retracted, and means for causing alternate needles of said other group to be partially advanced to receive yarn from said first yarn carrier while the remaining needles of said other group are retracted.
16. In a knitting machine, in combination, a plurality of yarn carriers for independent yarns, a series of groups of needles, all of the needles in each group being adapted to be advanced and retracted to interknit loops of certain of said yarns and alternate needles in each group being adapted to be advanced and retracted to place certain other of said yarns in position to be interlocked with the looped yarn without being knitted therethrough, means forming a part of said machine to operate all the needles of one group when certain of said yarn carriers are passing and to operate alternate needles of said group when certain other of said yarn carriers are passing, and means also forming a part of said machine to operate all the needles of an adjacent group when said certain other of said yarn carriers are passing and to operate alternate needles of said adjacent group when said certain of said yarn carriers are passing.
17. In a machine for incorporating a plurality of yarns into a fabric, in combination, a series of groups of latched needles, means to fully advance all the needles of certain of said groups and to retract the same, means operative subsequent to each operation of said aforesaid means partially to advance alternate ones of the needles previously actuated and to retract the same, means fully to advance all the needles of certain other of said groups and to retract the same,

- and means operative subsequent to each operation of the last-mentioned means partially to advance alternate ones of the needles previously actuated and to retract the same, whereby there is produced a fabric wherein each yarn presents a looped portion and a relatively straight portion, the relatively straight portion of each yarn extending along the rear of a portion of the fabric wherein certain of said yarns are looped, and being interlocked between certain of the loops thereof.
18. In a machine for combining a plurality of yarns into a fabric, in combination, a plurality of yarn carriers for independent yarns, a row of knitting units comprising yarn receiving members, each of said units having a latch associated therewith, and mechanism for operating said units, said mechanism including means to advance and retract the yarn receiving members of a group of adjacent units to cause the yarn carried by one of said yarn carriers to be received thereby and to be placed in association, with the latches of the respective units, means subsequently to advance and retract alternate yarn receiving members of said group of units to cause the yarn carried by a second of said yarn carriers to be received thereby and to be placed in association with the latches of the respective units, said latches being adapted to retain said first yarn during the operation of the last-named means, and means operative thereafter to actuate said units to cause the yarn retained by said latches to be removed therefrom and to be incorporated into the fabric, and means operative substantially simultaneously with the aforesaid means to advance and retract the yarn receiving members of a second group of said units to cause the yarn carried by said second yarn carrier to be received thereby and to be associated with the latches of the respective units, means subsequently to advance and retract alternate yarn receiving members of said second group to cause said first yarn to be received thereby and to be placed in association with the latches of the respective units, said latches being adapted to retain said second yarn during the operation of the last-named means, and means operative thereafter to actuate said units to cause the yarn retained by said latches to be removed therefrom.
19. In a machine for incorporating a plurality of independent yarns into a fabric, a series of groups of latched needles, means to advance and retract the needles of one group to receive one of said yarns and to knit loops thereof, means to advance certain of the needles of said group a distance sufficient to receive a second of said yarns but insufficient to allow the yarn previously looped thereby to escape therefrom, means to advance and retract the needles of another group to receive said second yarn and to knit loops thereof, and means to advance certain of the needles of said other group a distance sufficient to receive one of said independent yarns but insufficient to allow the yarn previously looped thereby to escape therefrom, whereby there is produced a fabric comprising a plurality of yarns, each presenting a looped portion and an unlooped portion, the unlooped portion of each yarn being interlocked with the looped yarn in certain of the wales thereof.
20. In an independent needle machine for combining a plurality of independent yarns into a fabric, in combination, a row of knitting units, each comprising a yarn receiving member and a latch, and means including said yarn receiving members and said latches to manipulate said yarns to produce a fabric wherein each yarn presents a looped portion and an unlooped portion, the unlooped portion of each yarn extending along the back of a section of the fabric wherein the looped portions of certain other of the yarns are interknit and being interlocked between the loops of adjacent rows in certain of the wales thereof.
21. In a machine for combining a plurality of yarns into a fabric, in combination, a plurality of yarn feeds for independent yarns, a row of knitting needles, mechanism for causing bodily movement of said needles, said mechanism including means for causing a group of adjacent needles to be placed in a fully advanced position to receive yarn at one of said feeds, means for causing another group of adjacent needles to be placed in a fully advanced position to receive yarn at a second of said feeds, means for causing certain of the needles of the first group to be placed in a partially advanced position to receive yarn at said second feed while the remainder of the needles of the first group are in a retracted position, and means for causing certain of the needles of said other group to be placed in a partially advanced position to receive yarn at said second feed while the remainder of the needles of said other group are in a retracted position, and mechanism operative periodically on the needle operating mechanism to reverse the operation of the same whereby said first group of needles are placed in a fully advanced position to receive yarn at the second of said feeds and placed in a partially advanced position to receive yarn at the first of said feeds, and whereby the operation of said mechanism on said other group of needles is reversed in a similar manner.
22. A knitting machine, including a row of needles each comprising a yarn receiving member and a shank, a plurality of separate yarn feeds for independent yarns, mechanism for moving said needles longitudinally

of said shank including means adapted to cause all of a group of adjacent needles to catch the yarn at one feed and knit loops thereof, means adapted subsequently to 5 cause alternate needles but not the remaining needles of said group to catch the yarn at a second feed without the formation of loops, means adapted to cause all of a second group of adjacent needles to catch 10 the yarn at said second feed and to knit loops thereof, and means adapted subsequently to cause alternate needles but not the remaining needles of said second group to catch the yarn at a yarn feed other than 15 said second feed without the formation of loops.

23. In a machine for combining a plurality of yarns into a fabric, in combination, a plurality of yarn feeds for independent 20 yarns, a row of needles each comprising a yarn receiving member and a shank, and being movable longitudinally of the shank to advanced positions wherein said yarns may enter said yarn **receiving** members, and 25 mechanism for operating said needles, said mechanism including means to cause one group of adjacent needles to be placed in an advanced position to receive yarn at one of said feeds, means for causing another group 30 of adjacent needles to be placed in an advanced position to receive yarn at a second of said feeds, means for causing interspersed needles of the first group to be placed in a partially advanced position to receive yarn 35 at said second feed while the remainder of the needles of the first group are in a retracted position, and means for causing interspersed needles of said other group to be placed in a partially advanced position to 40 receive yarn at said first feed while the remainder of the needles of said other group are in a retracted position, and means periodically to vary the operation of said mechanism whereby at least certain of the needles 45 of each group will be operated in a reverse manner at each of said feeds.

24. In an independent needle knitting machine, in combination, a row of needles, means adapted successively to feed to said 50 needles yarns of at least two different characteristics, means periodically to impart bodily movement to one group of adjacent needles to cause said needles to interknit loops of yarn of one character, means intermediately to impart bodily movement to certain of the needles of said group to cause 55 said certain needles to place yarn of a second character in position to be interlocked with the looped yarn while remaining unlooped, means periodically to impart bodily movement to a second group of adjacent needles to cause said needles to interknit loops of a 60 yarn of said second character, and means intermediately to impart bodily movement to certain of the needles of said second group 65

to cause said certain needles to place a yarn of said first character in position to be interlocked with the yarn looped by said second group of needles while remaining unlooped.

25. In an independent needle machine for combining a plurality of yarns into a fabric, in combination, a group of needles, mechanism for causing bodily movement of said needles, said mechanism including means to actuate said needles to cause them to interknit loops of certain of said yarns and to interlock unlooped portions of certain other of said yarns between the loops of said certain of said yarns in adjacent rows in certain of the wales thereof, and means to actuate said needles to cause them to interknit loops of said certain other of said yarns and to interlock unlooped portions of said certain of said yarns between the loops of said certain other of said yarns in adjacent 70 rows in certain of the wales thereof, and including adjustable members whereby each of said means may be rendered operative upon said needles to the exclusion of the other of said means, and means periodically to adjust said 75 adjustable members.

26. In a machine for combining a plurality of yarns into a fabric, in combination, a group of needles, mechanism for causing longitudinal movement of said needles, said mechanism including means to actuate said needles to cause them to interknit loops of certain of said yarns and to interlock unlooped portions of certain other of said yarns between the loops of said certain of said yarns in adjacent rows in certain of the wales thereof, and means to actuate said needles in a different manner, and including adjustable members whereby each of said 80 means may be rendered operative upon said needles to the exclusion of the other of said means, and means periodically to adjust said 85 adjustable members.

27. In an independent needle machine for combining a plurality of yarns into a fabric, in combination, a plurality of yarn feeds for independent yarns, a row of needles, means cooperating with said needles to manipulate said yarns to form a series of rows of interknitted loops of certain of said 90 yarns in one section of the fabric and to interlock unlooped portions of certain other of said yarns between loops in adjacent rows in alternate wales thereof, and to form a series of rows of interknitted loops of said certain other of said yarns in a second section of the fabric and to interlock unlooped portions of said certain of said yarns between loops in adjacent rows in alternate wales thereof, and means cooperating with said needles to manipulate the same yarns to form a series of rows of interknitted loops of said certain other of said yarns in a section of the fabric disposed longitudinally of certain of the wales of the first section.

tion and to interlock unlooped portions of said certain of said yarns between loops in adjacent rows in alternate wales thereof, and to form a series of rows of interknitted loops of said certain of said yarns in a section of the fabric disposed longitudinally of certain of the wales of said second section, and to interlock unlooped portions of said certain other of said yarns between 10 loops in adjacent rows in alternate wales thereof.

28. In a machine for incorporating a plurality of independent yarns into a fabric, a row of needles, means to impart longitudinal movement to said needles to cause a plurality of adjacent needles to knit loops of certain of said yarns and to interlock unlooped portions of certain other of said yarns therewith and to cause a plurality of other adjacent needles to knit loops of said certain other of said yarns and to interlock certain of said yarns therewith, said means comprising adjustable members whereby the particular needles knitting loops of each of said yarns may be varied, and means adapted to be operated continuously to effect an adjustment of said adjustable members from time to time.

29. The method of combining into a fabric the yarns carried by a plurality of yarn feeds, which comprises placing all of a group of adjacent members of a row of knitting needles in an advanced position to receive yarn at one of said feeds, placing only certain of the needles of another group in an advanced position to receive yarn at said feed, placing all the needles of said other group in an advanced position to receive yarn at a second of said feeds, and placing only certain of the needles of the first group in an advanced position to receive yarn at said second feed.

30. The method of combining a plurality of independent yarns into a fabric which comprises causing a group of adjacent members of a row of knitting needles to be fully advanced to receive one of said yarns, causing alternate needles of a second group to be partially advanced to receive said yarn, while the remainder of the needles of said second group are in a retracted position, and retracting the advanced needles, and thereafter causing all the needles of a second group to be fully advanced to receive another of said yarns, causing alternate needles of the first group to be partially advanced to receive said other yarn, while the remainder of the needles of the first group are in a retracted position, and retracting the advanced needles.

31. The method of combining into a fabric the yarns carried by a plurality of yarn feeds which comprises advancing and retracting a group of latched needles to cause them to catch the yarn at one of said feeds

and to knit loops thereof, subsequently advancing certain of the needles of said group a distance sufficient to catch the yarn at a second of said feeds but insufficient to permit the yarn previously caught to escape 70 from the latches thereof and retracting the same, and thereafter again advancing and retracting all the needles of said group to catch the yarn at one of said feeds and to knit loops thereof; substantially simultaneously advancing and retracting all the needles of a second group to catch the yarn at said second feed and to knit loops thereof, subsequently advancing certain of the needles of said second group a distance sufficient to catch the yarn at the first mentioned feed but insufficient to permit the yarn previously caught to escape from the latches thereof and thereafter advancing and retracting all the needles of said second group to cause them to catch the yarn at one of said feeds and to knit loops thereof; and at a later period of operation advancing and retracting all the needles of the first group to cause them to catch the yarn at said second feed, subsequently advancing certain needles of said first group a distance sufficient to catch the yarn at the first mentioned feed but insufficient to permit the yarn previously caught to escape from the latches thereof and retracting the same, and thereafter again advancing and retracting all the needles of said first group to catch the yarn at one of said feeds and to knit loops thereof; and substantially simultaneously advancing and retracting all the needles of said second group to catch the yarn at the first mentioned feed and to knit loops thereof, subsequently advancing certain needles in said second group a distance sufficient to catch the yarn at said second feed but insufficient to prevent the yarn previously caught to escape from the latches thereof and retracting the same, and thereafter advancing and retracting all the needles of the second group to cause them to catch the yarn at one of said feeds and to knit loops thereof.

32. The method of knitting into a fabric the yarns carried by a plurality of yarn carriers, which comprises advancing and retracting a group of latched needles to cause them to catch the yarn carried by one of said yarn carriers and to knit loops thereof, subsequently advancing alternate needles of said group a distance sufficient to catch the yarn carried by a second of said yarn carriers but insufficient to permit the yarn previously caught to escape from the latches thereof and retracting the same, and thereafter again advancing and retracting all the needles of said group to catch a yarn from one of said yarn carriers and to knit loops thereof, and substantially simultaneously advancing and retracting all the needles of a second group to cause them to catch the yarn carried by a third of said yarn carriers and to knit loops thereof, and thereafter again advancing and retracting all the needles of said second group to catch a yarn from one of said yarn carriers and to knit loops thereof.

neously advancing and retracting all the needles of a second group to catch the yarn carried by said second yarn carrier and to knit loops thereof, subsequently advancing alternate needles of said second group a distance sufficient to catch the yarn carried by the first of said yarn carriers but insufficient to permit the yarn previously caught to escape from the latches thereof and re-

tracting the same, and subsequently advancing and retracting all the needles of said second group to cause them to catch the yarn carried by one of said yarn carriers and to form loops thereof.

In witness whereof, I hereunto subscribe my name this 12 day of December A. D., 1922,

VINCENT LOMBARDI.
